UNITED STATES PATENT OFFICE

98,745

DESIGN FOR A PAPER HANDKERCHIEF OR SIMILAR ARTICLE

Charles A. Fourness, Appleton, Wis., assignor to International Cellucotton Products Company,
Chicago, Ill., a corporation of Delaware

Application November 13, 1935, Serial No. 59,524

Term of patent 14 years

To all whom it may concern:

Be it known that I, Charles A. Fourness, a citizen of the United States, residing at Appleton, county of Outagamie, and State of Wisconsin, have invented a new, original, and ornamental Design for a Paper Handkerchief or Similar Article, of which the following is a specification, reference being had to the accompanying drawing, forming a part thereof.

Fig. 1 is a plan view of a paper handkerchief embodying the new design.

Fig. 2 is a plan view of a portion of the article on an enlarged scale, approximately three times actual size, showing the new design in greater detail, and

Fig. 3 is a section on the line 3—3 of Fig. 2.

I claim:

The ornamental design shown for a paper handkerchief or similar article substantially as shown and described.

CHARLES A. FOURNESS.
